SPRAY GUN

Russell L. Potter, Toledo, Ohio, assignor to The
De Vilbiss Company, Toledo, Ohio, a corpora-
tion of Ohio

Application May 3, 1934, Serial No. 723,737

12 Claims. (Cl. 299—140.1)

This invention relates to spray-guns of the type employed for discharging surface coating materials in spray-form, and pertains more particularly, but not exclusively, to guns of this character adapted to discharge a fan-shaped spray stream.

An important object of the invention resides in the manner employed for directing and controlling the supply of air under pressure to the main and supplemental air discharge orifices of the gun head, and particularly the supply to said supplemental orifices, whereby the pressure of the air discharging from such orifices is uniform irrespective of the head adjustment or conditions of use.

Further objects and advantages of the invention will be apparent from the following detailed description of one embodiment thereof and from the accompanying drawing, in which—

Figure 1 is a central vertical longitudinal section of a spray-gun embodying the invention, with parts in full; Fig. 2 is an enlarged section on the line 2—2 in Fig. 1; Fig. 3 is an enlarged perspective view of the baffle means employed for uniformly distributing the air supply to the supplemental discharge orifices; Fig. 4 is an enlarged longitudinal section, with parts in full, of the valve means employed for controlling the supply of air to the spray-head, and Figs. 5 and 6 are different details of such means.

Referring to the drawing, A designates the gun body or stock having at its rear end the lateral projecting handle B, and at its forward end the enlargement C to which the spray-head D is attached.

Extending rearwardly through the body A from the upper portion of the enlargement C is a bore 1 for the passage of air, as hereinafter described, and below the forward end of such bore centrally of the enlargement C is a second bore 2 adapted to have suitable communication at its rear end with a source of material supply. An inner or material discharge nozzle 3 is threaded or otherwise suitably mounted at its inner end in the forward end of the bore 2. The discharge end of the nozzle 3 is encircled by an outer nozzle 4, which is spaced from the inner nozzle to provide an air passage 5 therearound and also an air discharge orifice 6 in concentric relation to the material discharge orifice of the nozzle 3. The nozzle 4 seats rearwardly against an annular flange 7 provided on the body of the inner nozzle 3 in advance of its point of connection with the body enlargement C, and the nozzle 4 is engaged at its outer rear edge by a union nut 8, which threads on a tubular ex-

tension 9 of the enlargement C concentric to the inner nozzle. The outer nozzle 4 is provided at each of diametrically opposite sides of its main discharge orifice 6 with a supplemental air discharge passage 10, which orifices direct jets of air in opposed relation against the combined air and material stream discharging from the inner nozzle 3 and orifice 6, as well understood in the art. The inner ends of the passages 10 communicate with an annular passage 11 provided in the nozzle 4 at 10 the outer side of the point of connection of such nozzle with the flange 7, so that there is no communication between the passage 11 and the inner annular air passage 5, which latter communicates with the orifice 6.

As is customary with spray-heads of this character, the outer nozzle 4 is adapted to have rotatable adjustment with respect to the inner nozzle, so as to flatten the spray stream in any plane desired to suit the work to be performed.

The tubular extension 9 on the enlargement C is spaced radially from the inner nozzle 3 and the portion of the enlargement C into which it threads to form an annular space therebetween, which space is divided into inner and outer annular chambers 12 and 13 by a tubular member 14, which has its rear end thrust against a coacting portion of the enlargement C and its forward end thrust against the flange 7 of the inner nozzle. The member 14 is centered with respect to the inner nozzle by seating at its forward end over an annular shoulder on the flange 7, as shown. The inner chamber 12 has communication with the passage 5 through a plurality of openings 15 provided in the flange 7, and the outer chamber 13 has communication at its forward end with the annular passage 11 from which the supplemental discharge passages 10 receive their air supply.

The outer chamber 13 receives its air supply at its rear end through a passage 16, which registers with the forward end of the body bore 1 and communicates therethrough with a source of air pressure supply, as hereinafter described.

In order to provide an even distribution of air under pressure to both supplemental discharge passages 10 under all conditions, the member 14 is provided at its outer side, within the chamber 13, with a plurality of successively disposed baffles, in the present instance, in the form of annular flanges 17, 18 and 19 (see Fig. 3), each having differentially arranged orifices therethrough, and which at their outer edges engage the tubular extension 9, so as to divide the chamber 13 into a plurality of annular passages.

In order to effect a thorough equalizing of the air pressure entirely around the forward end of the chamber 13 before entering the annular passage 11, the rear baffle flange 17 is provided with one or more orifices 17^a at opposite sides of the head axis and substantially a quarter way around in each direction from the air supply passage 16. The next flange 18 is provided equidistantly therearound with four notches 18^a, two of which 5 are above and two below the orifices 17^a. The last flange 19 is provided with a plurality of equidistantly spaced orifices 19^a of greater number than the passages 18^a and staggered with respect thereto. It is thus apparent that an efficient 10 uniform distribution of the air pressure to the forward end of the chamber 13 entirely around the spray-head axis is effected before such air passes to the annular passage 11, which directly supplies the air to the supplemental discharge 15 passages 10, thus causing a uniform distribution 20 of air pressure from the passages 10 irrespective of the position of adjustment of the outer nozzle.

The chamber 12 receives its air supply from the forward end of the bore 1 through an annular passage 20 and segmental passage 21 provided in the enlargement C concentrically of the bore 2, the passage 20 extending through the bottom portion of the bore 1 at its forward end to provide a port connection 22 therebetween.

30 A passage 25 is provided in the handle B for connection in any suitable manner, with a source of air pressure supply, and its passage has communication with a port 26 opening laterally into the rear end portion of the bore 1. A main normally closed shut-off valve 27 is provided in the passage 25, being opened by an operation of the trigger 28, as well understood in the art.

The bore 1 opens without the rear end of the gun body A and receives through such end a tube 30, which is threaded at its forward end in a slightly restricted portion of the bore 1 in advance of the port 22 with the forward end of its passage in communication with the orifice 16 through which air is supplied to the chamber 13, which latter may be considered as a pressure equalizing chamber. The rear end of the tube 30 is provided with an enlargement 31 that fits snugly in the rear end of the bore 1, and without the rear end of the bore the tube is provided with a further enlargement 32 that is adapted to shoulder against the marginal end wall of the bore and preferably has a portion of its periphery of hexagonal or other suitable form for engagement by a wrench to facilitate a turning of the tube into or out of threaded engagement at its forward end with the body enlargement C.

While the enlargement C has been referred to, in effect, as being a part of the body A, it, in reality, constitutes a head construction which is separable from the body A and is secured thereto by the tube 30, which acts as a bolt or rod for rigidly connecting the two parts of the gun body. This is a feature, which, in itself, forms no part of the present invention.

65 In order to prevent the tube 30 from falling out of the bore 1 and thus becoming separated from the gun body when the head construction C, D, is removed from the gun, the threaded end of the tube is slightly enlarged relative to the adjacent portion thereof and the bore is provided in the body A adjacent to its point of connection with the head C with a reduced threaded portion 33, thus requiring the tube to be unthreaded through such portion when being removed from the body. The tube 30 intermediate the inlet port

26 and outlet port 22 is smaller than the bore 1, so as to permit air to pass through the bore around the tube from one of said ports to the other. It is thus apparent that the only control for the air passing to the main air discharge orifice 6 of the spray-head is the main valve 27. 5

The tube 30 near its rear end portion has communication with the air space around the tube through ports 34, so that the supply of air for the supplemental discharge orifices 10 of the spray-head is furnished through the tube. The air for this purpose is controlled by a valve 35, which, in the present instance, is of tapered form and adapted to seat in a restricted portion of the tube passage provided slightly in advance of the ports 34 in the tube. The valve-stem is provided at its rear end portion with an enlargement 36 (Fig. 4), which in turn is provided intermediate its ends with a further enlargement 37 that is threaded into the rear end of the tube 30, so that a turning of the valve-stem relative to the tube will effect an advance or retracting of the valve relative to its seat. The outer end of the stem 36 projects from the rear end of the tube through a suitable packing gland 38 and is provided at its outer end with a knurled head 39 to facilitate turning.

It is desirable to provide some means for effecting a drag against a free turning of the valve-stem 36 so that the valve may not be accidentally moved from an adjusted setting found desirable for the particular spraying operation in hand. While it is not new to provide a drag on a valve of this character, the means heretofore employed for accomplishing this have, so far as I am aware, been unsatisfactory and impractical for many classes of work. An efficient means for accomplishing such a drag consists in mounting a skirt member 40 on the valve-stem 36 in advance of the threaded portion 37 and having its forward end slotted to provide spring fingers 41 which normally exert an outward pressure against the wall of the tube 30 and thus exert a considerable drag against a turning of the valve relative to the tube.

Another detailed construction of the valve mechanism that is of importance in connection with a tool of this character is the provision of an adjustable dial member in connection with the control head 39 of the valve. This member comprises a normal slightly cupped disk 45, which is held for rotatable adjustment within the outer recessed end of the valve-head by a screw 46. The edge of the disk is in contact with the bottom of the head recess and it is substantially flattened against the head by a tightening of the screw. The disk is of spring metal, so that when flattened, or partially flattened by the engagement of the screw, a sufficient binding action is provided between the valve-head and screw to prevent a free turning of the disk. The disk is provided with graduations which are adapted to register with some stationary point on the gun body to indicate the extent of turning adjustment of the valve-head relative to the body. It is found in practice that, due to variations in the machining of the various parts involved, it would be quite difficult and expensive to make the threading engagement of the tube 30 with the spray-head body, and the valve-stem 70 with said tube, and other relative dimensions of the various parts, so exact that a fixed dial on the valve and a marker line on the body would bear the same relation in a number of guns for the same amount of valve opening. It is also 75

found that there is considerable objection to removing valves after determining how they set in the valve body and then marking them. Replacement valves would also be a problem if such procedure were followed. These objections are obviated and the proper adjustment of the valves made simple and more or less permanent by the use of a dial disk 45 frictionally held to the valve-head. With this design of movable dial, should 10 wear of the valve or the valve-seat alter the standard original setting between the dial and the body mark, the dial may be easily and quickly reset to correspond to the original setting. To facilitate adjustment of the dial, a hole 47 is provided therein into which a pointed tool may be inserted.

It will be appreciated from the foregoing that in the use of my improved spray-gun, the operating air is supplied to the main and supplemental discharge orifices of the spray-head through distinct passages provided through a common bore in the gun body; that the air to the supplemental discharge orifices is controlled in a simple and convenient manner separate from the control means for the main air supply; that such control is located near the rear end of the gun body where it is convenient of access, and that the air for the supplemental discharge orifices passes through a pressure equalizing 25 chamber in the spray-head before reaching such orifices, so that the pressure is uniform in its discharge from both orifices irrespective of the position of such orifices. This latter is an important feature, as it obviates the objection frequently encountered in the use of spray-guns, that the pressure of air discharging from the two supplemental orifices varies, thus effecting the stream flattening efficiency of such air.

It is further apparent that with the present invention the tube 30 not only constitutes a means for detachably uniting the body A and spray-head portion C, D, of the gun, but also forms a passage for the air to a predetermined portion of the spray-head and constitutes with the control valve an assembly which is removable as a unit from the gun. It will be understood in practice that the valve 35 is set to suit the desired volume and pressure discharge of air from the supplemental orifices to suit the particular 50 job in hand.

Having thus described my invention, what I claim as new, and desire to secure by United States Letters Patent, is:

1. In a spray-gun, a body having a longitudinally extending bore therethrough and an air supply passage in communication therewith for connection with a source of air pressure supply, a spray-head detachably connected to the body and having main and supplemental air discharge orifices with respective distributing chambers in communication therewith, a member extended through said bore in shouldered engagement with a part thereof and having releasable engagement with the spray-head to unite the body and spray-head in assembled relation, said main and supplemental orifice distributing chambers having respective communication, one through said bore and the other through said member, with said supply passage, and means associated 70 with one of said passages for controlling the supply of air passing therethrough to the supplemental orifices.

2. In a spray-gun, a body having a longitudinally extending bore therein, a spray-head detachably carried by the body and having main

and supplemental air discharge orifices, a tubular member extending through said bore in engagement with a part thereof and having engagement at its forward end with the spray-head to retain the body and head in assembled relation, said main and supplemental passages adapted to have communication with a source of air pressure supply, one through said bore and the other through said member, and valve means cooperating with one of said passages to control 10 the supply of air to the supplemental orifices. 5

3. In a spray-gun, a body having a longitudinal bore therethrough and a passage adapted to open communication between said bore and a source of air pressure supply, a spray-head detachably carried by said body and having main and supplemental air discharge orifices, a tubular member extended through said bore in coaction with a portion of the body and having threaded engagement at its forward end with the spray-head to retain the body and spray-head in assembled relation, said main and supplemental discharge orifices having respective communication through said bore and tubular member with said supply passage, and a valve 20 mounted in said tubular member and operable from without the rear end of said member and bore to control the supply of air to said supplemental orifices. 25

4. In a spray-gun, a body having a longitudinal bore therethrough and a passage adapted to open communication between said bore and a source of air pressure supply, a spray-head detachably carried by said body and having main and supplemental air discharge orifices, a tubular member extended through said bore in shoudered coaction with a portion of the body and having threaded engagement at its forward end with the spray-head to retain the body and spray-head in assembled relation, said main and supplemental discharge orifices having respective communication through said bore and tubular member with said supply passage, and valve means carried by the tubular member to control the supply of air passing therethrough to 30 the supplemental orifices. 35

5. In a spray-gun, a gun body having a longitudinal passage therethrough adapted to have communication with a source of air pressure supply, a spray-head detachably carried by said body and having main and supplemental air discharge orifices, said main orifice having communication with the forward end of said longitudinal passage to receive its air supply therefrom, a tubular member mounted in said longitudinal passage and having detachable engagement with the spray-head to retain the spray-head and body in assembled relation, said member permitting the passage of air through said longitudinal passage without the member and 55 itself having communication at its forward end with the supplemental discharge orifices and at its rear end portion with a portion of the gun body through which air under pressure is supplied to said longitudinal passage. 60

6. In a spray-gun, a gun body, a spray-head, a tubular member projected through the body and operable to unite the body and head in assembled relation and forming an air supply passage to a portion of the spray-head, a valve 70 mounted in said member to control the passage of air therethrough and having a stem part projecting without the rear end of the tube and threaded in the tube, whereby a turning of the stem effects an adjustment of the valve, and 75

drag means carried by the stem and having a yielding portion in frictional engagement with said member to resist a turning of the stem.

7. In a spray-gun, a gun body, a spray-head carried thereby and having main and supplemental air discharge orifices and separate air chambers therefor, said body having a bore extending rearwardly from the spray-head with its forward end in communication with one of said chambers and its rear end in communication with a source of air pressure supply, a tube mounted in said bore and forming a separate passage from the bore in communication at its forward end with the other of said chambers and at its rear end with the source of air pressure supply, and means associated with said tube to regulate the volume of air passing therethrough.

8. In a spray-gun, a gun body, a spray-head carried by the body at its forward end, said head having main and supplemental air discharge orifices and a separate air chamber for each, said body having a bore extending rearwardly therein from adjacent the spray-head and forming an air passage with its forward end in communication with one of said chambers, a tube extending rearwardly in said bore from adjacent the spray-head and forming a second air passage with its forward end in communication with the other of said chambers, said bore and tube passages having communication rearwardly of the head with an air pressure supply source.

9. In a spray-gun, a gun body, a spray-head carried by the body at its forward end, said head having main and supplemental air discharge orifices and a separate air chamber for each, said body having a bore extending rearwardly therein from adjacent the spray-head and forming an air passage with its forward end in communication with one of said chambers, a tube extending rearwardly in said bore from adjacent the spray-head and forming a second air passage with its forward end in communication with the other of said chambers, said bore and tube passages having communication rearwardly of the head with an air pressure supply source, means for regulating the supply of air to both said passages, and a separate means for regulating the passage of air through one of said passages.

10. In a spray-gun, a gun body having a spray-head at one end and a handle at the other end, said head having main and supplemental air discharge orifices and separate air supply chambers therefor, said body having a bore extending rearwardly from adjacent the head and forming an air passage with its forward end in communication with one of said chambers, a tube on said

bore forming a second air passage with its forward end in communication with the other of said chambers, said passages adapted for common communication at their rear end portions with an air pressure supply source through said handle, a main control valve carried by the handle for the supply of air to said passages, and a second control valve mounted in the rear end of said bore and controlling the passage through said tube.

11. In a spray-gun, a body part having a material supply throat in its forward end, a material discharge nozzle projecting from said throat and having an annular flange in advance of the body part, said part having an annular abutment rearwardly of said nozzle flange and a forward extension without said abutment flange and outwardly spaced with respect to said nozzle, a tubular member in abutment at its ends with said flanges and dividing the space between said nozzle and extension into inner and outer air chambers, an outer nozzle encircling the outer end of said inner nozzle and having rearward abutment against said first annular flange and providing a main discharge orifice, said outer nozzle also having supplemental air discharge passages, and means releasably joining the outer nozzle to the body part, said main air discharge orifice having communication through said inner air chamber and said supplemental passages having baffled communication through said outer chamber with a source of air pressure supply.

12. In a spray-gun, a body part having a material supply throat in its forward end, an annular extension without said throat and concentric thereto and an annular abutment internally and rearwardly of said extension, an inner material discharge nozzle projecting from said throat and having an annular flange in advance of said abutment, a tubular member in opposite end abutment with said flange and abutment and dividing the space between said nozzle and extension into inner and outer air chambers, a plurality of flanges on said member dividing said outer chamber into a plurality of annular passages having staggered communication with each other through the flanges, an outer air discharge nozzle in rearward abutment against said first flange and having a main air discharge orifice associated with the inner nozzle discharge and having supplemental air discharge orifices, said main orifice having communication through said inner air chamber and said supplemental orifices having baffled communication through said outer air chamber with a source of air pressure supply.

RUSSELL L. POTTER.
